UNITED STATES PATENT OFFICE.

CHARLES E. HATHAWAY, OF MURPHYSBORO, ILLINOIS.

GAS-ENGINE.

1,112,371.

Specification of Letters Patent. Patented Sept. 29, 1914.

Application filed July 8, 1913. Serial No. 777,881.

To all whom it may concern:

Be it known that I, CHARLES E. HATHAWAY, a citizen of the United States, residing at Murphysboro, in the county of Jackson and State of Illinois, have invented new and useful Improvements in Gas-Engines, of which the following is a specification.

This invention relates to internal combustion engines the object in view being to provide novel and effective valve mechanism for controlling the intake and exhaust of the gases, the said valve mechanism being contained wholly within the engine and concealed thereby and operating silently and with precision.

A further object of the invention is to provide a valve shell operating between the piston and the cylinder wall, combined with driving mechanism for revolving said valve shell at the proper rate of speed consistent with the cycle of operation; also means for maintaining the proper compression in the combustion chamber and preventing the leakage of the gas during the explosion and compression strokes of the piston.

A further object of the invention is to provide a system of gearing between the crank shaft and valve shell for imparting rotary motion to the valve shell; also means for adjusting the lead between the valve shell and crank shaft, or in other words advancing or retarding the valve shell with respect to the rotation of the crank shaft and consequently the movements of the piston.

A further object of the invention is to so arrange the parts hereinabove referred to as to enable the working faces thereof to be properly lubricated.

With the above and other objects in view, the invention consists in the construction, combination and arrangement of parts, as will hereinafter be more fully described, illustrated and claimed.

In the accompanying drawings Figure 1 is a vertical diametrical section through an internal combustion engine embodying the present invention. Fig. 2 is a cross section on the line 2—2 of Fig. 1. Fig. 3 is a cross section on the line 3—3 of Fig. 1. Fig. 4 is a detail perspective view of the valve sleeve. Fig. 5 is a detail view of the compression shell.

The crank case of the improved engine is indicated at 1, 2 designating the cylinder, 3

the piston mounted to reciprocate therein, 4 the connecting rod, 5 the wrist pin, 6 the crank shaft and 7 the crank to which the connecting rod 4 is attached.

In carrying out the present invention, the crank case 1 is provided adjacent to the top thereof with a lateral cylindrical offset 8 to provide space for a spiral gear wheel 9 which is fast on a valve shell operating shaft 10 journaled in suitable bearings in the crank case, and mounted for longitudinal movement for a purpose which will hereinafter appear. The shaft 10 is driven from the crank shaft 6 by means of a silent chain 11 which passes around a wheel 12 on the crank shaft and another wheel 13 of the shaft 10, the wheel 13 being provided with a square central hole 14 through which a correspondingly squared portion 15 of the shaft 10 is adapted to slide, the wheel 13 being sustained against lateral movement by any convenient mechanical expedient.

The bore of the cylinder 2 is materially larger than the external diameter of the piston 3 for the purpose of enabling a valve shell 16 in the form of a hollow cylinder to be interposed between the piston and cylinder wall as shown in Fig. 1, the piston being provided with the usual piston rings 17 which work in contact with the inside wall of the valve shell 16.

The valve shell 16 has fast on the lower end thereof a spiral gear wheel 18 which meshes with the wheel 9 and is driven thereby. In a four-cycle engine the wheel 18 revolves at one half the speed of the wheel 9 and at one half the speed of the crank shaft 6 so that the valve shell will be carried through one complete revolution for each complete cycle of operation of the piston 3 which, in a four-cycle engine, has four complete strokes back and forth for each explosion or impulse. The wheel 18 is of course centrally apertured as shown at 19 to allow ample clearance for the movement of the connecting rod 4.

At a suitable point, the valve shell 16 is offset or enlarged forming an annular shoulder 20 which bears against a corresponding internal annular shoulder 21 within the cylinder as shown in Fig. 1. This sustains the valve in proper relation to the inlet and exhaust ports of the cylinder while permitting said valve to revolve freely around the piston. The shell 16 extends outwardly into the cylinder head 22 which is formed sepa-

rately from the main body of the cylinder and secured thereto by cap screws 23 or their equivalent. The valve shell 16 is also internally enlarged or rabbeted as shown at 5 24 to provide for the reception of a compression shell 25 in the form of a thin hollow cylinder split or divided at one side to enable said compression shell to be compressed and set into the outer portion of the shell 16. In order to prevent the gas either 10 while being compressed or exploded from passing around the outer extremity or edge of the valve shell 16, a compression ring 26 is set into a recess or annular groove 27 in the cylinder head, said compression ring bearing at all times against the compression shell and lying in close contact therewith. The cylinder is water-jacketed as shown at 15 28 and the cylinder head is also water-jacketed as at 29.

The working parts just hereinabove described are easily lubricated by passing oil or other lubricating material through a supply pipe 30 having two branches 31 and 32. 25 The branch 31 leads through the cylinder wall and also through a port 33 in the valve shell so as to supply the lubricant between the working faces of the valve shell 16 and the compression shell 25. The branch 32 30 leads through the cylinder wall and introduces the lubricant between the working faces of the valve shell 16 and the cylinder wall, the latter being formed with an oil duct or groove 34 extending lengthwise 35 thereof so as to insure the carrying of the oil throughout the length of the valve shell and cylinder wall. The lubricating oil is dumped into the crank case by passing over the gear wheel 18 and is carried back to the 40 pipe 30 or a tank from which the pipe 30 leads off by any suitable oil pump (not shown).

The compression shell 25 is provided with an inlet port 35 and an exhaust port 36 45 which register with an inlet port 37 and an exhaust port 38 in the cylinder. The valve shell 16 is provided with a port 39 which, during the rotation of said valve shell, registers first with the inlet port and afterward with the exhaust port, the valve shell being of course properly timed to open the intake port during the suction stroke and the exhaust port during the scavenging stroke.

The lead between the valve shell 16 and the crank shaft 6 may be adjusted and varied by a longitudinal movement of the shaft 10 which does not effect a shifting of the wheel 13 but which does shift the spiral gear on said shaft and as said 55 60 last named gear moves in one direction or the other, it of course acts to partially turn the wheel 18 in one direction or the other. This has the effect of advancing or retarding the valve shell in relation to the rotation 65 of the crank shaft 6 thus presenting the

port 39 of the valve shell earlier or later into register with the inlet and exhaust ports of the cylinder and the compression shell 25.

From the foregoing description it will 70 be understood that the crank shaft 6 imparts rotary motion to the shaft 10 through the silent chain 11. The spiral gears on the shaft 10 and the valve shell 16, cause said shell, in a four-cycle engine, to turn at 75 one half the speed of the crank shaft. In each complete revolution of the valve shell 16, the port therein registers at different times with the intake and exhaust ports, allowing a charge of gas to be sucked into 80 the combustion chamber during the suction stroke of the piston, and allowing the burnt gases to be expelled through the exhaust port during the scavenging stroke of the piston. The valve shell thus acts noiselessly 85 as does the chain 11, all of the working parts of the valve mechanism being contained wholly within the crank case and cylinder of the engine. The compression shell 25 taken in connection with the compression ring 26 90 prevents leakage of gas during the compression and explosion strokes and thereby maintains the proper compression in the combustion chamber.

The cylinder, in the preferred embodiment of the invention is formed separately from the crank case 1 and bolted or otherwise fastened thereto. The wheel 18 is preferably pressed upon the lower portion of the valve shell and will ordinarily be 100 keyed in place thereon so as to insure the simultaneous rotation of said parts. This enables the wheel 18 to be removed from the shell 16 in order to detach the latter from the cylinder which may be done by 105 removing the cylinder head.

The working faces of the piston, cylinder, valve shell and compression shell are easily and perfectly lubricated in the manner hereinabove described and the usual splash system may be employed in the crank case for lubricating the piston, crank shaft, wrist pin and connecting rod bearings, as well as the gears 13 and 18 and the chain drive 11. 110

The engine hereinabove described operates very silently and on account of the simplicity and minimum number of parts very few and very simple patterns are all that is necessary to produce the engine. Furthermore the engine is very compact and will 115 also be found unusually economical in fuel consumption in view of the fact that there are practically no cavities for the gas to enter and burn other than the space directly over the piston. For these reasons the engine will be capable of long and hard service with very little adjustment and repair, there being no delicate parts to get out of order while at the same time the engine 120 125 is capable of being manufactured of light 130

weight combined with the necessary strength to impart long and hard service thereto.

The purpose of retarding or advancing the valve shell in relation to the crank, 5 is to admit and discharge the gases at an earlier or later point of crank travel. Where as much power as possible is desired at a slow speed of the engine, retarding the valve or port opening in relation to the crank 10 cause the gases to be retained in the cylinder until the piston reaches its extreme point of travel on its power stroke before the exhaust ports are open. Where very high speed of the engine is desired or 15 necessary, the valve shell may be advanced and the gases may be admitted at an earlier point of crank travel, which will allow the engine to clear itself more freely at high speed. What is meant by the engine clearing itself more freely is to allow the burnt gases to be discharged at an earlier point 20 of crank travel, or get out of the cylinder before the piston starts up on the exhaust stroke. With this type of valve in retarded 25 position the gases will be admitted later,

which is necessary to attain perfect carburation at slow speed of the engine, and at high speed, with the valve advanced, the gases will be admitted earlier which is practicable on account of the rapid movement 30 of the piston.

What is claimed is:

In an internal combustion engine, the combination of a crank shaft, a cylinder provided with an internal valve abutment shoulder, a reciprocating piston, a cylindrical valve operating between the piston and cylinder wall and ported to register with the intake and exhaust ports of the cylinder, an annular external shoulder on 35 said valve engaging said internal shoulder of the cylinder, a cylindrical compression shell arranged interiorly of said valve shell, and means for operating said valve.

In testimony whereof I affix my signature 40 in presence of two witnesses.

CHARLES E. HATHAWAY.
